(57) **CLAIM**

The ornamental design for a string spool for a string trimmer (brush cutter), as shown and described.

DESCRIPTION

The patent or application file contains at least one drawing executed in color. Copies of this patent or patent application publication with color drawing(s) will be provided by the Office upon request and payment of the necessary fee.

1. String spool for string trimmer

1.1 : Perspective

1.2 : Top

1.4 : Front

The design concerns a string spool for a string trimmer (brush cutter) with a multi color string with different color in different sections of the string.
